[57] CLAIM

The ornamental design for an automobile body, as shown and described.

DESCRIPTION

FIG. 1 is a left side and front perspective view of an automobile body showing our new design;

FIG. 2 is a left side view of an automobile body of FIG. 1, it being understood that the opposite side to that shown is a substantial mirror image;

FIG. 3 is a front view of an automobile body of FIG. 1;

FIG. 4 is a top view of an automobile body of FIG. 1;

FIG. 5 is a right side and rear perspective view of an automobile body of FIG. 1; and,

FIG. 6 is a front perspective view of a second embodiment of an automobile body showing our new design, it being understood that the second embodiment is identical to the first embodiment except that the roof tubes have been removed.

It being understood that the broken line showing of the wheels and tires throughout the drawings is for illustrative purposes only and forms no part of the subject invention.
